UNITED STATES PATENT OFFICE.

ROY F. OTT, OF SACO, MAINE.

CLEANER FOR WARPING MACHINES AND BEAMERS.

Application filed March 7, 1923. Serial No. 623,372.

The invention relates to a new and useful improvement in cleaners for warping machines and beamers. In warping machines and beamers there is a constant tendency for the accumulation of flies, so-called, in the drop wires or yarn. These flies consist of particles of lint usually caused by the yarn chafing against the drop wires or other mechanisms. If they are allowed to accumulate on the drop wires or yarn they will clog the wires and produce knots or bunches on the yarn causing imperfect goods and sometimes leading to breaking of the yarn which necessitates stopping of the machine. It is important, therefore, that the wires and threads be kept as free as possible from such accumulations.

One feature of the invention consists in constructing the cleaner in the form of a rotary fan having a plurality of blades in different radial planes, there being a plurality of blades in longitudinal series in each of said planes spaced apart from each other endwise and breaking joints with those in the adjacent planes, thereby producing a peculiar variation in the breeze produced by the fan which is more effective in blowing away the particles of lint than if the fan blades of each series are uninterrupted. Another feature of the invention consists in the manner in which the blades are mounted, the blades being mounted upon a shaft in such manner as to be both adjustable longitudinally of the shaft and interchangeable. Another feature of the invention relates to the drive for the cleaner. Other features will be more particularly described hereinafter.

The invention will be fully understood from the following description when taken in connection with the accompanying drawings, and the novel features thereof will be pointed out and clearly defined in the claims at the close of this specification.

As illustrating one use of the invention, it is shown in the drawings as employed in connection with a warping machine, but it is to be understood that the invention is not limited to such use.

In the drawings:

Fig. 1 is a perspective view of a warping machine embodying the invention.

Fig. 2 is a plan view of the fan and its intermediate bearing.

Fig. 3 is a front elevation of the parts shown in Fig. 4.

Fig. 4 is a detail view enlarged of one of the collars which supports the fan blades.

Fig. 5 is a fragmentary view on an enlarged scale of the fan shaft and the attached blades.

Fig. 6 is a section on line 6—6, Fig. 5.

Fig. 7 is a section on line 7—7, Fig. 5.

Fig. 8 is a section on line 8—8, Fig. 5.

Referring now to the drawings, there is shown at 9 a warp beam of ordinary construction, at 2 are shown the wires which form the ravel or comb through which the warp threads 3 pass from the spools 34 to the beam 9, and at 4 are shown the drop wires. The comb wires 2 are secured to the back or rail 5. All of the parts above mentioned are of well-known form of construction.

The cleaner which forms the particular subject-matter of the invention consists of a plurality of fan blades mounted on a rotary shaft 6. Preferably, it is driven by suitable connections by the same power which drives the warp beam, as will be more particularly described hereinafter.

The power for rotating the warp beam is furnished in any suitable manner. It is shown as transmitted from a pulley 7 through intermediate gear and pinion connections, as will be more particularly described hereinafter.

The cleaner blades are radial to the shaft 6 and form a rotary fan. Preferably, there are at least four sets of these blades disposed in planes at 90° apart. Instead of making the blades continuous the entire length of the shaft, there are preferably provided a series of shorter blades with spaces between the adjacent ends of those in each series, and they are arranged so that the spaces between the ends of any two adjacent blades will be covered by some of the blade sections in an adjacent series, except that there is an open space 30 to avoid interference with the middle bearing 31 and its support where an intermediate bearing is employed. The intermediate bearing may however be omitted, and in such case the space 30 will be covered by some of the blades. Further, it is preferable that the several blade sections in each series shall be in slightly different planes from each other.

The cleaner shaft 6 is journaled in suitable bearings somewhat below and in front of the drop wires 4 and comb 2, and preferably just above the warp beam 9. As shown in the drawings, said shaft is journaled at its ends in the standards 10, 10, and has an intermediate bearing 31 mounted on a bracket 32 secured to the rod 33. The fan shaft, therefore, extends at both ends 10 a sufficient length so that the cleaner will extend the full length of the warp beam.

The blades are preferably secured to the shaft 6 by means of a series of star-shaped collars or sleeves 11, having radiating arms 12 preferably at 90° apart. The said collars are formed as sleeves slidable on said shaft so as to be adjustable to any position desired, both axially and radially, and are secured in their adjusted positions by means of set 20 screws 13. A sufficient number of collars is mounted on the shaft to permit a plurality of blades of varying length to be arranged in longitudinal series the length of the shaft. For instance, as shown, there is a series of 25 blades 14¹, 14², 14³ in one series, and blades 15, 15¹, 15², 15³ in another series which are in a plane substantially 90° from those in the first series. Another longitudinal series 30 16, 16¹, 16², 16³ are in planes at substantially 180° from the first series, and a series 35 17, 17¹ in a plane substantially at right angles to the plane of the third series. In order to make a very slight variation in the planes of those in each series, some of them are attached to the front face of the radial arms 12 of the collars, and some of them are attached to the rear faces of the radial arms, so that there will be thin spaces between the planes of different blades in the same 40 series equal to the thickness of the arms 12.

As will be readily seen from the drawings, the blades in each series are of varying lengths and there are open spaces between the adjacent ends of all of the blades in each series. The blades 14, 14¹, 14², 14³ break joints with, that is, cover the spaces between the ends of the blades 15, 15¹, 15², 15³ and with the blades 17, 17¹, except across 50 the open space 30 which is left for the intermediate bearing 31, as already described. The same method of arrangement so as to break joints is employed in each of the other series of blades.

It is obvious that the blades may be varied in number and length and relative location in each series, the important feature being that there shall be open spaces in the series lengthwise, and that these open spaces shall be lapped over by the blades in another series.

The pulley 7 is driven from any suitable source of power through a belt 18. The shaft 6 is driven by the pulley 7 through intermediate connections. The driving

means shown is as follows:—The pulley 7 is mounted on a shaft 19 on which is also mounted a pinion 20. Said pinion 20 meshes with a gear 21 mounted on a shaft 22. The gear 21 meshes with a pinion on a shaft 24 which carries the pulley 25. The pulley 25 is connected by a belt with a pulley 26 mounted on the fan shaft 6.

By reason of the several open spaces between the blades of the different series and the arrangement in different planes of those in the same series, the air is blown in irregular puffs and in different currents at different points in the length of the fan by the different series of blades. This results 80 in a peculiar succession of thumps or beats instead of one continuous, steady blast and also produces a greater breeze, and is much more effective in clearing the particles of lint from the drop wires and from the 85 threads.

There is a clearance space between the path of the blades and the drop wires, preferably about four inches, and the blades clear the yarns slightly more than they clear 90 the ends of the wire.

The cleaner is a sufficient distance from the yarn so that the breeze made by the cleaner does not in any way interfere with the proper winding of the yarn onto the beam, regardless of whether the yarn winds onto the beam from underneath or onto the top. By placing the fan in this position, it will not interfere with the operative and is, therefore, much safer and lessens the danger 100 of accident. Heretofore, the position and form of warper cleaners have been such as to be dangerous to the operative and increase the cost of the accident insurance and sometimes the cost is prohibitive.

By mounting the blades on the adjustable collars and by making them in series, not only is there obtained the advantages already described, but the cost of upkeep is lessened. For instance, if any one of the blades is broken it can be replaced at comparatively slight expense. Instead of having to replace a blade which extends the entire length of the fan shaft it is necessary only to replace a relatively short blade, while the remaining blades in the series continue in use. Another advantage of mounting the blades in this manner is that they may be adjusted to varying distances apart from each other, both radially and axially, according to whatever experience shows to be most desirable in any particular case.

For some kinds and grades of yarn, the speed required in order to keep the drop wires clean is different from the speed required in other cases. The number, counts or size of yarns, the grade of cotton and the speed of the warper determine the speed of the cleaner, as the object in view is to operate the cleaner at a sufficient rate of speed 130

to prevent the accumulation of particles of lint in the drop wires or on the threads, as heretofore mentioned. The speed of the fan may be varied by varying the size of the gears and pulleys.

While I have specifically described this invention as applied to a warping machine, it is adapted to be used in connection with beamers as well as warpers for cotton, 10 worsted and woolen or any other textile or fibrous material.

What I claim is:—

1. A rotary fan consisting of a plurality of series of blades mounted on a rotary shaft 15 and projecting outwardly therefrom in different planes parallel with the axis of the shaft, the blades in each series having spaces between their adjacent ends, the blades of one series being in a plane at an angle to the plane of those in the adjacent series and 20 breaking joints with and covering the spaces between the blades of the adjacent series, the blades being of varying lengths in a direction parallel with the shaft. 25

2. A rotary fan consisting of a plurality of series of blades mounted on a rotary shaft and projecting outwardly therefrom in dif-

ferent planes parallel with the axis of the shaft, the blades in each series having spaces between their adjacent ends, the blades of one series being in a plane at an angle to the 30 plane of those in the adjacent series and breaking joints with and covering the spaces between the blades of the adjacent series, the blades being of varying lengths in a direction parallel with the shaft. 35

3. A rotary fan comprising a rotary shaft, a series of adjustable collars mounted on said shaft, each of said collars having arms radiating therefrom, and a plurality of blades secured to said arms, there being a 40 plurality of blades in lengthwise series as well as in radial series with relation to the shaft, some of the blades in each lengthwise series being secured to one face of said arms, and other blades in the same lengthwise 45 series being secured to the opposite faces of said arms, whereby the blades in the same lengthwise series are disposed part in one plane and part of them in another plane, said two planes being parallel to each other. 50

In testimony whereof I affix my signature.

ROY F. OTT.
